UNITED STATES PATENT OFFICE.

ZENE R. MAULSBY AND JOHN R. MAULSBY, OF EVERETT, WASHINGTON.

FABRIC-FORMING MACHINE.

Application filed March 30, 1927. Serial No. 179,576.

This invention relates to improvements in machines for shirring cloth and other fabrics or materials; more particularly, the invention relates to a machine for forming fabric into designs suitable for decorative purposes, such as for the lining of caskets or the like; the present invention being in the nature of an improvement over the device shown in our pending application, 5 Serial Number 58,354, filed September 24, 10 1925.

It is the principal object of the invention to provide a machine for the above stated purpose, embodying a plurality of parallel gather bars, each bar mounting a plurality 15 of gatherers, or pattern blocks, and wherein the fabric is formed about the gatherers and is held there by the application of an air current against the fabric while it is tacked 20 to a suitable backing piece which serves to retain the design, or pattern, in the fabric after it has been removed from the machine.

Other objects of the invention reside in the various details of construction and combination of parts as will hereinafter be 25 described.

In accomplishing the various objects of the invention, we have provided the improved 30 details of construction, the preferred forms 30 of which are illustrated in the accompanying drawings, wherein—

Figure 1 is a perspective view of a shirring machine embodied by this invention.

Figure 2 is an enlarged, vertical section 35 of a part of the same, showing the manner of mounting the gatherers, or pattern blocks, on the gather bars.

Figure 3 is a perspective view showing the 40 chains for connecting the gatherers on the gather bars.

Figure 4 is a fragmental plan view of the machine, with parts broken away for better illustration.

Figure 5 is a perspective view of a gather 45 bar and gatherer of an alternative form.

Referring more in detail to the drawings—

1 designates a rectangular frame, or table, supported at a suitable working height by legs 2 at its four corners. The frame comprises longitudinal, opposite side beams 3—3 and opposite end rails 4—4; the latter having strips 5 fastened to their outer surfaces and extended above the top surface and provided, along their top edges, with 50 inturned flanges 5' beneath which the opposite ends of a plurality of gather bars, pres-

ently described, are adjustably held. Each of the gather bars comprises a pair of parallel rods 6—6 joined at their ends by connecting pieces 7. These bars are disposed 60 lengthwise of the frame in parallel relation, with their ends resting on the end rails 4—4 beneath the flanges 5' of the plates 5, so that they may be adjusted from and toward each other. 65

Slidably mounted on each of the bars for movement lengthwise thereof, is a plurality of pattern blocks, or gathers, 10. Preferably, these are stamped from sheet metal and each comprises a flat base portion 10^a 70 that overlies the bar and which has downwardly and inwardly curled, opposite edge portions 10^b which form guide channels within which the rods 6—6 of the bar are slidably contained. At one end of the base 10^a is an extension 11 that projects upwardly and over the base and is then bent back to provide a horizontal top portion 12 in which a plurality of upwardly extending pins 14 are fixed. The top portions 12 of all of the 75 gatherers lie in the same horizontal plane and they may be made in various designs, or shapes, such as rectangular, square, round, or in characteristic designs of clover leaf, diamond, or oval form as is desired. 80

The gatherers of each bar are connected with each other by means of short chains 18, or the like, each of which has an end link fastened in the base of one block and has a hook 19 at its opposite end adapted to 90 be removably applied to an aperture in the edge portion of the adjacent block. This form of connection is provided in order that the blocks on each bar may be moved closely together and, when they are adjusted to 95 extended relation, may be limited equally in their spaced apart relation.

Disposed above the table, is an air hood 25. This has a flat under wall 26 of substantially the same dimensions as the table, and is provided with a plurality of perforations through which air may be discharged 100 downwardly against the table. The hood is of pyramid form and at its apex is connected with a pipe 27 through which air, under pressure, may be supplied to the hood. 105

In using the device, the gather bars are first adjusted to spaced apart, parallel relation so that they extend across the top surface of the table. The gatherers are then 110 adjusted to extended relation by drawing them apart the distance provided for by the

connecting chains. The piece of cloth to be Shirred is then placed over the blocks and bars while they are in this extended relation. Air is then delivered to the hood and 5 is directed forcibly through the apertures in the under wall of the hood against the cloth so that it will be pressed downwardly against the pattern blocks and pins in the latter projected into the cloth. While the 10 air is thus being directed against the cloth, the gather bars are moved toward each other and the gatherers are also adjusted along the bars toward each other to produce the desired Shirring or gathering effect in the 15 cloth. During this adjusting process, the air current retains the cloth against the blocks and prevents it from slipping from the pins in the latter, so that it may be formed about the top pieces of the blocks 20 and will conform to the design of the latter. After the adjustment has been made and while the air current is still in force, a back- 25 ing piece of material, as designated at 30, is placed over the Shirred piece and is tacked thereto by use of a needle and thread, so 30 that the design will be retained on the cloth after it has been removed from the machine.

In Figure 6, we have shown an alternative form of gatherer and gather bar in which 35 the rods 6-6 are of inwardly opening, channel form and the opposite edges of the base portion of the gatherer block are slidably contained within the channels.

Having thus described our invention, what 35 we desire to obtain by Letters-Patent, is:

1. A fabric Shirring machine comprising 40 a plurality of movably mounted pattern blocks arranged in spaced relation to present a surface over which a piece of fabric may be spread and means disposed above 45 said surface for directing an air current against the fabric to form it about the blocks.

2. A fabric Shirring machine comprising 45 a plurality of movably mounted pattern blocks arranged in spaced relation to present a surface over which a piece of fabric may be spread, pins in the blocks adapted for projection into the fabric and an air hood disposed over the said surface, provided with perforations through which air 50 may be directed forcibly against the fabric to form it about the blocks.

3. A fabric Shirring machine of the character described comprising a horizontal frame, a plurality of gather bars disposed in parallel relation on the frame and adjustable from and toward each other, a plurality of pattern blocks mounted on each 55 bar and adjustable therealong from and to-

ward each other, said blocks presenting a surface over which a piece of fabric may be spread, an air hood disposed above the surface having a horizontal bottom wall with perforations therein through which air may 65 be forcibly directed against the fabric to form it about the pattern blocks.

4. A fabric Shirring machine of the character described comprising a horizontal frame, a plurality of gather bars disposed in parallel relation on the frame and adjustable from and toward each other, a plurality of pattern blocks mounted on each bar and adjustable therealong from and toward each other, said blocks presenting a surface over 70 which a piece of fabric may be spread, an air hood disposed above the surface having a horizontal bottom wall with perforations therein through which air may be forcibly directed against the fabric to form it about 75 the pattern blocks and flexible means connecting the pattern blocks of each bar whereby their spaced relation is limited.

5. A device of the character described comprising a rectangular frame with guide 85 flanges fixed to its opposite ends, a plurality of gather bars mounted in parallel relation on the frame with their ends disposed adjustably beneath said flanges, a plurality of pattern blocks mounted on each of the 90 bars and adjustable therealong, flexible means connecting the blocks of various bars whereby they may be drawn to extended 95 relation and whereby the spaced relation of the blocks on a bar is limited, said blocks having top surfaces of various designs and 100 pins projecting upwardly from said surfaces, said blocks presenting a surface over which a cloth may be spread for Shirring and an air hood disposed in spaced relation closely above the surface, having its bottom wall provided with perforations through which air may be forcibly discharged against a cloth to form it about the pattern blocks.

6. In a machine of the character described, 105 a Shirring bar comprising parallel, spaced apart rods and pattern blocks mounted adjustably on said bars for movement longitudinally thereof, said blocks each comprising a base portion with inturned edge flanges 110 forming channels wherein the said rods are slidably contained and having an upwardly directed portion overlying the base and a horizontally extending top portion with pins projecting upwardly therefrom.

Signed at Everett, Washington, this 10th day of Jan., 1927, and at Minneapolis, Minn., this 4th day of January, 1927.
